R. M. ALBRIGHT.

BRAKE ATTACHMENT FOR AUTOMOBILES.

APPLICATION FILED NOV. 8, 1915.

1,202,639.

Patented Oct. 24, 1916.

UNITED STATES PATENT OFFICE.

ROBERT M. ALBRIGHT, OF ELMINS, WEST VIRGINIA.

BRAKE ATTACHMENT FOR AUTOMOBILES.

1,202,639.

Specification of Letters Patent. Patented Oct. 24, 1916.

Application filed November 8, 1915. Serial No. 60,399.

To all whom it may concern:

Be it known that I, ROBERT M. ALBRIGHT, a citizen of the United States, residing at Elkins, in the county of Randolph, State of West Virginia, have invented certain new and useful Improvements in Brake Attachments for Automobiles; and I do hereby declare the following to be a full, clear, and exact description of the invention, such as will enable others skilled in the art to which it appertains to make and use the same.

The present invention is directed to improvements in brake attachments for Ford automobiles, and has for its object to so construct a device of this character that it can be easily and quickly attached to a car of this make, and when in place thereon will operate in an efficient manner.

A further object of the invention is to provide a band brake attachment which can be attached to the car without removing the usual brake drums carried thereby.

A still further object of the invention is to provide a novel means for supporting the rock shaft of the attachment whereby the strain imparted thereto during the operation of the brake will be equalized between the differential housing and the rock shaft.

Still another object is to provide a bearing for the rock shaft which can be easily and quickly attached to the differential housing when the same is being assembled.

With these and other objects in view, this invention resides in the novel features of construction, formation, combination and arrangement of parts to be hereinafter more fully described, claimed and illustrated in the accompanying drawing, in which:

Figure 1 is a rear elevation of the automobile showing the same equipped with the device. Fig. 2 is a sectional view on line 2-2 of Fig. 1. Fig. 3 is a similar view on line 3-3 of Fig. 1. Fig. 4 is a similar view on line 4-4 of Fig. 1. Fig. 5 is a sectional view through one of the drums. Fig. 6 is a sectional view through the usual brake drum and auxiliary band.

Referring to the drawing 1 indicates the rear tubular axle housing and 2 the differential housing. The hubs of the rear wheels have fixed thereto in the usual manner the brake drums 3. To the drums 3 are fixed the metal bands 4 of my attachment, and

since the same are formed from metal they can be produced at a very small cost. 55

The usual housings 5 have bolted thereto brackets 6, said brackets having carried thereby bearings 7 for receiving the rock shaft 8, the outer ends of which have attached thereto collars 9, said collars having 60 oppositely directed arms 10 and 11 carried thereby. The arms 10 have pivotally connected thereto links 12, said links being adjustably connected to the webs 13 of the angle plates 14, which are fixed to one of 65 the ends of the brake band 15, said brake band being lined with suitable fabric. The arms 11 are pivotally connected to the other ends of the brake band, whereby when the shaft 8 is rocked the band will be caused to 70 expand or contract, and since the same are engaged around the bands 4 carried by the drum 3 it is obvious that the braking action of the vehicle can be readily controlled.

The rock shaft has fixed thereto an arm 75 16, which is pivotally connected to the rear end of the rod 17, which is controlled by the usual foot lever (not shown). The rod 17 is yieldably connected to the bottom of the vehicle by a coil spring 18, which serves to 80 normally hold the shaft 8 in a position to hold the bands 15 in an expanded position. To prevent the brake bands 15 from moving laterally guides 19 are provided, said guides being bolted to the rear radius rod 20. The 85 bearing block 21 is triangular in shape, and has formed on its rear end a transverse groove 22 for receiving the rock shaft 8. Circular plates 23 are provided and are connected to the rims 23' of the differential 90 housing by one of the bolts 24, said plates having formed integral therewith diverging arms 25 which are secured to the sides of the block 21. Thus it will be seen that the strain imparted to the rock shaft will be 95 equalized between the brackets 6 and said bearing.

From the foregoing description it will be seen that a brake attachment has been provided for a motor vehicle which is constructed in such a manner that it can be conveniently applied and will eliminate the hub brake shoes now used on the vehicle. 100

What is claimed is:—

The combination with a vehicle having its 105 drive wheels provided with drums, brake

bands engaged with the drums, a rock shaft having its ends connected with the brake bands, a triangular shaped bearing block having its inner edge engaged with the differential housing, a transverse groove formed in the outer end of the block for receiving the shaft, plates bolted to the differential housing and having spaced arms car-

ried thereby for attachment to the sides of the block.

In testimony whereof, I affix my signature, in the presence of two witnesses.

ROBERT M. ALBRIGHT.
